UNITED STATES PATENT OFFICE

109,843

DESIGN FOR A DECORATIVE COVE STRIP

Gerald K. Geerlings, New Canaan, Conn.

Application February 25, 1938, Serial No. 75,408

Term of patent 14 years

To all whom it may concern:

Be it known that I, Gerald K. Geerlings, a citizen of the United States, residing at New Canaan, in Fairfield County, State of Connecticut, have invented a new, original, and ornamental Design for a Decorative Cove Strip, of which the following is a specification, reference being had to the accompanying drawing, forming a part thereof.

Fig. 1 is a perspective view of a length of the decorative cove strip showing my new design.

Fig. 2 is a vertical sectional view of the strip as shown in Fig. 1.

Fig. 3 is a perspective view of the strip of Fig. 1 in reversed position.

Fig. 4 is a vertical sectional view of the strip as shown in Fig. 3.

I claim:

The ornamental design for a decorative cove strip, as shown and described.

GERALD K. GEERLINGS.
